CONTROLLING MECHANISM FOR WORK-POSITIONING MEANS.

1,404,190.

Specification of Letters Patent.

Patented Jan. 24, 1922.

Application filed March 17, 1919. Serial No. 283,149.

To all whom it may concern:

Be it known that I, IRA C. BUCKMINSTER, a citizen of the United States, residing at Beverly, in the county of Essex and State 5 of Massachusetts, have invented certain Improvements in Controlling Mechanism for Work-Positioning Means, of which the following description, in connection with the accompanying drawings, is a specification, 10 like reference characters on the drawings indicating like parts in the several figures.

My invention relates to controlling mechanism for work-positioning means, as for the band-clamps which, in heel-attaching 15 machines, correctly locate with relation to the nailing mechanism a lasted shoe supported upon a jack-post. These band-clamps are commonly joined to the jack-post, as by a chain, for movement thereby, being lowered under the influence of gravity when the 20 jack-post carrying the shoe to which the heel is to be attached is swung into the nailing position, and being elevated out of the path of the nail-transferring mechanism 25 when the jack-post is oppositely moved for the reception of another piece of work. To correctly engage and position the shoe, the lower edge of the band is adapted to enter the rand-crease, and to permit this when the 30 lasts vary in height, it is necessary for the operator to alter the relation of the band-clamp to the jack-post, as by changing the effective length of the connecting chain.

The present invention has for an object 35 the elimination of such a manual adjustment of a work-positioning member, and the provision of means whereby the band-clamp or other positioning means will be caused to engage the work properly when its dimensions vary.

As a feature of the invention, there is 40 combined with a work-support and a work-positioning member, novel means for controlling said positioning member in accordance with a characteristic of the work or its 45 relation to the support. For this purpose, a controlling member may contact with the work to govern the positioning member, and, if the variation is in height, the contact may 50 be at the opposite side of the work from the support. If the work consist of a lasted shoe, this contact will be with the heel seat, it controlling the positioning member, as the band-clamp, independently of the effect of

the work-support, or jack-post. In the illustrated embodiment, the controlling member, as well as the positioning member, is movable under the influence of the work-support, but preferably at a different rate therefrom and during at least a portion of 60 its travel in the opposite direction. This permits it to be brought into engagement with and measure work of varying dimensions. In so doing, it may set movement-limiting means in advance of the positioning member, thereby determining the extent 65 of movement of the latter. In the illustrated heel-attaching machine, a gage-plate actuated with the band-clamp by the jack-post is brought by a differential travel, produced by gearing in the connections, against 70 the heel seat of whatever height of lasted shoe may be upon the jack-post, and a stop set by said gage-plate, which stop is engaged by an element carried by the band- 75 clamp.

To obtain the desired measuring effect, as another feature of the invention, I interpose the controlling member in a novel manner between the work-support and the means 80 for operating upon the work, and, to avoid interference with this operating means, the controlling means is movable out of the path of the support and operating means, it thus 85 preferably having a movement toward and from the work-support to effect its measuring or stop-setting function, and a lateral movement with respect to the support to carry it clear of the operating means. The controlling means may have co-operating 90 with it, means, as a spring, for forcing it toward one extreme of movement, it being there temporarily retained or latched at the opposite extreme, and, to shift the controlling means to its latched position, there is 95 herein disclosed means under the influence of the work. To release the controlling means, there is shown means under the joint influence of the work, the work-positioning means and the controlling means itself, though this 100 action may be accomplished by fewer elements. In a heel-attaching machine there may, as to this feature, be combined with nailing mechanism, a jack-post and a band-clamp, a gage-plate or other controlling member movable between the nailing mechanism and jack-post, with a spring exerting its 105 force to move the plate toward these elements

and a latch for retaining the plate clear thereof. There is an actuator for releasing the latch and also an actuator for setting the plate against the tension of the spring. A 5 pawl is shown traveling with the gage-plate for engagement with teeth connected with the band-clamp. The engagement of the pawl with the teeth is governed by an actuating element moved by the band-clamp 10 under the influence of the work. The actuator for the gage-plate is also preferably movable by the band-clamp.

As a further feature of the invention, there is provided means for retaining the controlling means for the measuring means in its work-measuring relation. This allows, for example, moving the controlling means from between the work and mechanism operating thereon after the stop for the positioning means has been set by contact of the controlling means with the work, without disturbing such setting. This retaining or locking of the controlling means may be through the instrumentality of a clutch, and, 20 in the heel-attaching machine disclosed herein, co-operating clutch elements are carried by a supporting element and the gage and stop mechanism by which the band-clamp is controlled. I prefer to operate the clutch 25 by movement of the jack-post and contact of the work thereon, the actuating means being shown as connected to the band-clamp.

Other features will be evident upon consideration of the following description illustrated by the accompanying drawings, in which

Fig. 1 is a side elevation of a portion of a heel-attaching machine including one embodiment of the invention, the jack-post 40 being in its work-receiving position;

Fig. 2 is a similar view, with the jack-post in the operating or nailing position, parts being broken away;

Fig. 3 is a perspective view of the band-clamp with its support and more closely co-operating parts;

Fig. 4 is a horizontal section on the line 4—4 of Fig. 1;

Fig. 5 is a vertical section on the line 50 5—5 of Fig. 1; and

Fig. 6 shows co-operating elements of the clutch actuator separated from one another.

There appears at 10 the work-spindle of a heel-attaching machine, it being mounted for 55 reciprocation in the usual manner and having fixed to its lower end a head 12. In ways in this head is adjustably mounted a slide 14. Between lugs 16 depending therefrom is pivoted a jack-post 18. When in 60 its forward position, the jack-post may have placed upon it a lasted shoe, indicated at S, the shoe and last together being considered for the purposes of the present invention to constitute the work operated upon. At its 65 other extreme of movement, as illustrated in

Fig. 2, the jack-post presents the shoe to nailing mechanism, of which a nail-block 20 and drivers 22 only are shown, these inserting the nails which attach the heel H. To position the shoe correctly with relation to the heel held over the nail-block, a band-clamp mechanism is provided, which generally does not differ essentially from what has been heretofore employed. I have shown a band 24 arranged to contact with 75 the counter portion of the shoe upon opposite sides, the lower edge of the band entering the rand-crease, the engaged shoe thus being located both horizontally and vertically for the nailing operation. The band is pivoted upon arms 26 mounted for adjustment by a screw 27 upon a transverse extension 28 at the lower extremity of a slide 30, this slide being vertically movable in a supporting and guiding member 32. The support 32 is adjustable by a screw 34 in a horizontal direction to determine the location of the work transversely of the machine upon the lower end of a vertical arm 36, the upper portion of which is movable on the 90 slide 14, toward and from the jack-post to properly locate the work in this direction, by a screw 38 and clamped in its adjusted position by a screw 40. The band-clamp, 95 through the slide 30, is joined in the customary manner to a hook 42 projecting from the top of the jack-post by a chain 44 passing over a sprocket wheel 45 rotatable at the rear of the slide 14. This connection causes the band-clamp to be raised above the path of the nail-loading mechanism (not illustrated) when the jack-post is in the inactive or work-receiving position illustrated in Fig. 1, and, to permit said band-clamp to fall by gravity into the work-positioning relation shown in Fig. 2, when the jack-post is shifted to the operating or nailing position. The vertical relation of the band to the work, so that the lower edge may be aligned with the rand-crease, is effected by hooking different links of the chain 44 upon the hook 42 or, more exactly, by turning a screw 46 threaded into the top of the slide 30 and having a head resting upon a terminal 48 of the chain. 110

It will be clear that, unless the connection between the jack-post and band-clamp is changed when the height of the last within the shoe applied to the jack-post varies, the lower edge of the band will be either above 115 or below the rand-crease of the shoe, and the band will not properly engage and position the work. To overcome this difficulty, my novel controlling mechanism is employed. In the band-clamp slide 30 is a vertical way 50 for a sliding carrier member 52, which bears a stop-member 54 projecting through a vertical slot 56 in the front of the slide 30. With this member 54 a stop-projection 58 upon the slide 30 co-operates, there prefer- 120 125 130

ably being a screw 60 threaded vertically through the projection 58 and serving to alter the point at which the stop arrests the movement of the band-clamp mechanism, 5 and thus controls the relation of the band to the work for any particular adjustment of the band-clamp connections. The screw 60 may be fixed in its adjusted position by a set screw 62 threaded through the side of 10 the projection 58. Motion is imparted to the slide 52 from the jack-post by a chain 64 joined to an adjusting screw 66, operating similarly to the screw 46. This chain 64 passes over a sprocket 68, mounted to 15 turn independently beside the sprocket 45, and at its opposite or upper end is attached to an arm 70 fixed to a shaft 72 rotatable in lugs 74 at the upper rear portion of the jack-post. Fast upon the shaft 72 is a 20 pinion 76 meshing with a gear-segment 78 formed upon one of the lugs 16, this gearing causing the rotation of the arm 70 and the consequent raising or lowering of the controlling slide 52 as the jack-post is oscillated. Included in the chain 64 is a spring 25 80, the purpose of which will later appear.

To determine the location of the stop 54 and, therefore, the extent of descent of the band-clamp in accordance with a characteristic of the work, in the present instance the height of the last or the distance of the heel seat portion from the surface resting against the end of the jack-post, there is a gage mechanism contacting with the work 30 to measure it. At the bottom of the slide 52 are brackets 82, 82 spaced from one another transversely of the machine, upon which brackets are pivoted, at 84, horizontal gage-plates 86, 86. Tension springs 88, 35 extending between arms 89 of the plates and projections 91 from the lower end of the slide, exert their force to turn the plates toward one another about their pivots until flanges 90 at their upper faces contact with 40 or are adjacent to the sides of the band 24. The setting action of this gage and stop mechanism is as follows: When the jack is in its work-receiving position (Fig. 1), the arm 70 connected to the chain of the slide 52 is 45 substantially horizontal. As the jack-post moves inwardly toward the nailing position, the hook 42 rises and permits the band-clamp slide to fall by gravity at the same rate as the jack-post moves. Because, however, of the action of the gearing 76, 78, the 50 arm 70 moves more rapidly than does the hook 42, its travel being first upward. The slide 52 carrying the gage plates 86 therefore falls more rapidly than does the band-clamp, traveling down the way 50, this continuing until it has reached a position below the band 24 sufficient to provide for the measuring of the highest last which may be employed in the work. At this time, the 55 arm 70 has reached its highest position and

begins to move to the left, as viewed in Figs. 1 and 2, now exerting a positive pull upon the chain 64, and therefore raising the slide 52. As the jack-post has now carried the shoe over the plates 86, the upward movement of the slide brings them against the heel seat, this occurring before the jack-post is in its vertical position. Further movement of the arm 70 simply draws the plates 86 more firmly against the shoe, the spring 75 80 yielding to permit this. The stop 54 is thus located by the gage-plates at a point determined by the height of the last, this having been accomplished before the jack-post reaches the operating position. 80

To free the heel seat of the shoe for the attachment of the heel, the plates are moved clear of the work and nailing mechanism, and this I prefer to bring about under the influence of the travel of the jack-post and work. Secured to the rear of the band 24 at 98 and guided by a stem 92, which reciprocates in a guide sleeve 94 threaded into the slide 30, is an actuating member 96. This member has lateral arms 100, 100, from 90 the outer extremities of which depend contact pins 102 through openings 104 in the plates 86. The pins rest against the edges of the openings which are curved at 106 to form cam surfaces. When the shoe, in the 95 rearward travel of the jack-post to the nailing position, contacts with the band-clamp, moving it inward, the member 96 is carried with it, and the pins 102, bearing upon the cam surfaces 106, turn the gage-plates 86 100 about their pivots so they are swung to opposite sides of the shoe and the nail-block, clearing the intermediate space for the nailing operation. 100

Having thus freed the work of the gage-plates, it is desired to temporarily retain them in their inactive position for a time independently of the pressure of the work upon the band. In a rearward extension 108 of each plate is an opening 110 for engagement by a latch pin 112 movable vertically in a socket 114 formed upon the bottom of the slide 52. A spring 116, surrounding each latch pin within its socket, tends to force it downward so it may enter the corresponding opening 110. 110

Since, after the plates pass from beneath the work, their location-determining effect upon the stop 54 is lost, it is necessary to first independently fix the stop in its set position. For this purpose, the support 32 carries at its lower rear portion, in a casing 118, clutch members 120, shown as multiple plates mounted upon a stud 122 projecting from the side wall of the casing. The opposite casing wall 124 is movable with the controlling slide 52 and has a stud 126 supporting plates 128 interleaved with the plates 120. As a primary actuator for this clutch mechanism, the member 96 connected to the 120 125 130

band-clamp may be utilized. Upon the rear extremity of the stem 92 is a head 130, rectangular in form and best shown in Fig. 6 of the drawings, arranged to slide in a vertical way 132 in the front face of a head 134 carried upon a stem 136. This last-mentioned stem is guided for horizontal movement in a perforated boss 138 projecting from the outer face of a cover-plate 140 for 10 the casing 118. The stem 136 moves between plates 142 depending from the stud 126 and has at one side, toward the clutch-plates 128, cam surfaces 144, which contact with oppositely inclined surfaces 146 upon one 15 of the plates 142. From this last-mentioned cam-plate, bosses 148 project toward the adjacent clutch-plate 128, and surrounding the bosses and contacting at their ends with the plates are springs 150. These springs, when 20 the plate 142 is moved under the influence of the cam-surfaces, act to force the plates 128 into clutching engagement with the companion plates 120 and thus lock the slide 52 to the relatively fixed support 32. The cam- 25 surfaces are sharply inclined, as a result of which, as soon as the contact of the work with the band 24 moves back the member 96 and its stem 92, the plate 142, through its bosses, produces engagement of the clutch- 30 plates, fixing the controlling slide with the stop 54 in the position to which it has been adjusted by the gage-plates, before these plates are moved by the pins 102 and cam surfaces 106 out of contact with the heel- 35 seat of the shoe. After the clutch has thus locked the gage and stop mechanism, interference with the final engagement of the band with the work, because the actuator sections 92 and 136 are fixed to the band-clamp 40 and support, respectively, is avoided by the movement of the head 130 in the way 132.

After the completion of the nailing operation, the gage-plates must be released from their latches so that the springs 88 may restore the plates to their normal position. This preferably takes place after the shoe operated upon has reached a point in the forward movement of the jack-post beyond the gage-plates, so that, upon their release, 45 the edges of the plates will not strike the upper of the shoe, thus avoiding the possibility of their marring it. To accomplish this deferred release, I may employ the differential movement between the slides 30 and 52. 50 Pivoted to the latch pins 112 is a lever 152, fulcrumed at 154 upon the side of the slide 52. The lever is divided at 156 and between the arms is pivoted a pawl 158 projecting upwardly through an opening 160 in the stem 92 of the actuating member 96. 55 The pawl may be moved into engagement with a vertical series of ratchet teeth 162, carried upon the rear face of the band-clamp slide 30. After the nailing opera-

tion, when the heeled shoe is withdrawn 65 from the band-clamp by the forward movement of the jack-post, the band, traveling for a time with it in engagement with the shoe and acting through the member 96 and stem 92, turns the pawl 158 about its pivot 70 until its upper end engages the ratchet teeth 162. During the earlier portion of the differential movement of the slides 30 and 52, the latch pins 112 are unaffected, but when, 75 after the shoe has passed beyond the ends of the plates 86 as the slide 52 moves up more quickly than does the slide 30, the fulcrum 154 of the lever 152 rises at a more rapid rate than does the rear end, held by the pawl. This swings the lever about its 80 fulcrum, lifting the latch pins out of the openings 110 and releasing the gage-plates 86, which are swung by their springs 88 to their normal positions, as illustrated in 85 Figs. 3 and 4. In the reverse movement of the jack-post, when the extreme of travel is nearly reached, the movement of the actuator 96 and stem 92 by the band-clamp under the influence of the supported shoe, 90 forces the forward edge of the stem opening 160 against the pawl, releasing it from the ratchet teeth and allowing the springs 116 to force the pins into the openings 110. This release does not occur until the pins are above the surfaces of the plate arms 108, 95 so they fall upon these and ride over them into the openings.

The complete operation of the apparatus will only be generally outlined. The operator applies the jacked shoe to be heeled 100 to the jack-post and swings it from the position of Fig. 1 to that of Fig. 2. The band-clamp is allowed to fall toward its shoe-receiving position, while the gage and stop mechanism first falls more rapidly, to with 105 certainty reach a point below whatever shoe is to be operated upon, and then is drawn up into contact with its heel-seat. Toward the end of the movement of the jack-post and under the control of the actuator 96, 110 the stop mechanism is locked by the clutch-plates, the gage-plates are forced clear of the work, and the latch pins are released and caused to retain the gage-plates in the position for the nailing operation. When the 115 screw 60 contacts with the set projection 54, the lower edge of the band will be located exactly opposite the rand-crease of the shoe, as determined by the measurement effected by the gage-plates, and this controlling operation will be automatically performed for each height of last applied to the jack-post. The heel having been attached, the jack-post is swung out, withdrawing the band, 120 releasing the clutch for the stop mechanism, and tripping the latches for the gage-plates, which are returned to their springs to position for another operation. 125

- Having described my invention, what I claim as new and desire to secure by Letters Patent of the United States is:
1. In a machine of the class described, a work-support, a work-positioning member, and means governed by a characteristic of the work for controlling the relation of the positioning member to the work.
  2. In a machine of the class described, a work-support, a movable work-positioning member, and means movable independently of the positioning member and dependent upon the relation of the work to the support for determining a limit of the movement of the work-positioning member.
  3. In a machine of the class described, a work-support, a work-positioning member, a controlling member contacting with the work to determine the location of the positioning member, and means for fixing the controlling member in its location-determining position.
  4. In a machine of the class described, a support for a lasted shoe, positioning means for engagement with said shoe, and movable controlling means for the positioning means limited in its movement by contact with the heel-seat of the shoe.
  5. In a machine of the class described, a movable work-support, a movable work-positioning member, connections to the work-support for imparting the work-positioning movement to the member, and controlling means for the positioning member movable into contact with the work.
  6. In a machine of the class described, a movable work-support, a movable work-positioning member, movable controlling means for the positioning member, and connections to the work-support arranged to move the work-positioning member and controlling means.
  7. In a machine of the class described, a movable work-support, a movable work-positioning member, controlling means for the positioning member, and connections including a yieldable element between the positioning member and controlling means, and work-support for moving said member under the control of said means.
  8. In a machine of the class described, a movable work-support, work-positioning means movable under the influence of the support, and controlling means for the positioning means mounted to move upon said positioning means.
  9. In a machine of the class described, a movable work-support, work-positioning means movable under the influence of the support, and controlling means for the positioning means mounted to move upon said positioning means and being actuated by the support.
  10. In a machine of the class described, a movable work-support, a movable work-po-
  11. In a machine of the class described, a movable work-support, a work-positioning member movable under the influence of the support, controlling means for the positioning member movable by the support at a different rate from the positioning member, and connections between the support and member for effecting the movements.
  12. In a machine of the class described, a movable work-support, a work-positioning member movable under the influence of the support into position to receive the work, and controlling means for the positioning member movable by the support oppositely to the direction of movement of the positioning member and into contact with the work.
  13. In a machine of the class described, a movable work-support, a work-positioning member movable under the influence of the support, and controlling means for the positioning member movable at a different rate from the positioning member and in the opposite direction.
  14. In a machine of the class described, a work-support, a work-positioning member movable to prepare it to receive contact of the work on the support, movement-limiting means for the positioning member, and means for setting the movement-limiting means.
  15. In a machine of the class described, a work-support, a work-positioning member movable to prepare it to receive contact of the work on the support, movement-limiting means for the positioning member, and means for setting the movement-limiting means with but in advance of the movement of the positioning member.
  16. In a machine of the class described, a work-support, a movable work-positioning member, movement-limiting means for the positioning member, and connections to the support for setting the movement-limiting means.
  17. In a machine of the class described, a work-support, a movable work-positioning member, movement-limiting means for the positioning member, and means movable into contact with the work for setting the movement-limiting means.
  18. In a machine of the class described, a work-support, a movable work-positioning member, movement-limiting means for the positioning member, and means connected to the support and controlled by the work for setting the movement-limiting means.
  19. In a heel-attaching machine, a jack-post, a band-clamp, and a controlling member for the band-clamp governed in its position by a characteristic of the work.

20. In a heel-attaching machine, a jack-post, a band-clamp, and a controlling member for the band-clamp contacting with the work.
- 5 21. In a heel-attaching machine, a jack-post, a band-clamp, and a controlling member for the band-clamp contacting with the work at the side opposite the jack-post.
- 10 22. In a heel-attaching machine, a jack-post to receive a lasted shoe, a band-clamp, and a controlling member for the band-clamp contacting with the heel-seat of the shoe.
- 15 23. In a heel-attaching machine, a jack-post, a band-clamp, a controlling member for the band-clamp, and independent actuating connections between the jack-post and band-clamp and between the jack-post and controlling member.
- 20 24. In a heel-attaching machine, a jack-post, a band-clamp, a controlling member for the band-clamp, and differential actuating connections between the jack-post and band-clamp and between the jack-post and controlling member.
- 25 25. In a heel-attaching machine, a jack-post, a band-clamp, a controlling member for the band-clamp, independent actuating connections between the jack-post and band-clamp and between the jack-post and controlling member, and a spring included in the connections for the controlling member.
- 30 26. In a heel-attaching machine, a jack-post, a slide, a band-clamp mounted thereon, and a movement-limiting member for the band-clamp movable upon the slide.
- 35 27. In a heel-attaching machine, a jack-post, a slide, a band-clamp mounted thereon, and a controlling member for the band-clamp having a portion traveling upon the slide and a portion extending below the band-clamp.
- 40 28. In a heel-attaching machine, a jack-post, a slide, a band-clamp mounted thereon, and a controlling member for the band-clamp movable upon the slide, and connections between the controlling member and jack-post.
- 45 29. In a heel-attaching machine, a jack-post, a band-clamp, a controlling member for the band-clamp, and connections including gearing arranged to transmit movement between the jack-post and controlling member.
- 50 30. In a heel-attaching machine, a jack-post and its supporting slide, a band-clamp, a movable controlling member therefor, gear-teeth carried by the slide, a shaft journaled in the jack-post, a pinion mounted upon the shaft and engaging the teeth of the slide, and connections between the shaft and controlling member.
- 55 31. In a heel-attaching machine, a jack-post and its supporting slide, a band-clamp, a movable controlling member therefor, gear-teeth carried by the slide, a shaft journaled in the jack-post, a pinion mounted upon the shaft and engaging the teeth of the slide, and connections between the shaft and controlling member.
- 60 32. In a heel-attaching machine, a jack-post, a band-clamp, a movable stop contact with an element movable with the band-clamp, and connections to the jack-post for moving the stop.
- 65 33. In a heel-attaching machine, a jack-post for supporting a lasted shoe, a slide, and a band-clamp mounted on said slide, the slide having a way, a carrier movable in the way and being provided with a stop for the slide, and means for determining the position of the carrier.
- 70 34. In a heel-attaching machine, a jack-post, a band-clamp-slide and its supported band-clamp, there being a way in the slide, a member movable in the way and being provided with a stop-surface, the stop-member having a portion projecting below the band-clamp, and means arranged to adjust the stop member in its way.
- 75 35. In a heel-attaching machine, a jack-post, a band-clamp-slide and its supported band-clamp, there being a way in the slide, a member movable in the way and being provided with a stop-surface, a contact-member having a portion projecting below the band-clamp, and connections between the contact-member and jack-post.
- 80 36. In a heel-attaching machine, a jack-post, a band-clamp-slide and its supported band-clamp, there being a way in the slide, a member movable in the way and being provided with a stop-surface, a contact-member having a portion projecting below the band-clamp, and connections including a spring between the contact-member and jack-post.
- 85 37. In a heel-attaching machine, a jack-post, a band-clamp-slide and its supported band-clamp, there being a way in the slide, a member movable in the way and being provided with a stop-surface, a contact-member having a portion projecting below the band-clamp, and connections including gearing between the contact-member and jack-post.
- 90 38. In a machine of the class described, a work-support, means for operating upon the work, a positioning member acting upon the work carried by said support, and means for controlling the work-positioning member interposed between the support and operating means.
- 95 39. In a machine of the class described, a work-support, means for operating upon the work, the work-support and operating means being relatively movable toward and

from one another, a positioning member acting upon the work carried by said support, and means for controlling the work-positioning member interposed between the support and operating means and being movable out of their path of movement.

40. In a machine of the class described, a work-support, means for operating upon the work, the work-support and operating means being relatively movable toward and from one another, a carrier, a work-positioning member mounted thereon, and means for controlling the work-positioning member interposed between the support and operating means and being movable toward and from the support and laterally with respect to said support.

41. In a machine of the class described, a work-support, means for operating upon the work, the work-support and operating means being relatively movable toward and from one another, a carrier, a work-positioning member mounted thereon, means for controlling the work-positioning member interposed between the support and operating means and being movable transversely of their path of movement, and means for forcing the controlling means toward one of the extremes of movement.

42. In a machine of the class described, a work-support, means for operating upon the work, the work-support and operating means being relatively movable toward and from one another, a work-positioning member, means for controlling the work-positioning member interposed between the support and operating means and being movable transversely of their path of movement, and means under the influence of the work for forcing the controlling means toward one of the extremes of movement.

43. In a machine of the class described, a work-support, means for operating upon the work, the work-support and operating means being relatively movable toward and from one another, a work-positioning member, means for controlling the work-positioning member interposed between the support and operating means and being movable transversely of their path of movement, means under the influence of the work for forcing the controlling means toward one of the extremes of movement, and a spring forcing the controlling means toward the opposite extreme of movement.

44. In a machine of the class described, a support and operating means for engaging the work, a work-positioning member, means for controlling the work-positioning member, said controlling means being movable toward and from the path of the work-engaging members, means for normally forcing the controlling means toward said path, and means arranged to move the controlling means out of the path.

45. In a machine of the class described, a work-support, means for operating upon the work, the work-support and operating means being relatively moveable toward and from one another, a work-positioning member, means for controlling the work-positioning member interposed between the support and operating means and being movable out of their path of movement, means for forcing the controlling means toward one of the extremes of movement, and means for temporarily retaining the controlling means near the other extreme of movement.

46. In a machine of the class described, a support and operating means for engaging the work, a work-positioning member, means for controlling the work-positioning member, said controlling means being movable toward and from the path of the work-engaging members, means for normally forcing the controlling means toward said path, and means for temporarily retaining the controlling means out of said path.

47. In a machine of the class described, a work-support, means for operating upon the work, the work-support and operating means being relatively movable toward and from one another, a work-positioning member, means for controlling the work-positioning member interposed between the support and operating means and being movable out of their path of movement, means for forcing the controlling means toward one of the extremes of movement, means for temporarily retaining the controlling means near the other extreme of its movement, and automatic means for releasing the retaining means.

48. In a machine of the class described, a work-support, means for operating upon the work, the work-support and operating means being relatively movable toward and from one another, a work-positioning member, means for controlling the work-positioning member interposed between the support and operating means and being movable toward and from the support and laterally with respect to said support, means for temporarily retaining the controlling means against lateral movement, and means actuated in the movement of the controlling means for releasing the retaining means.

49. In a machine of the class described, a work-support, means for operating upon the work, the work-support and operating means being relatively movable toward and from one another, a work-positioning member, means for controlling the work-positioning member interposed between the support and operating means and being movable toward and from the support and laterally with respect to said support, means for temporarily retaining the controlling means against lateral movement, and means actuated in the movement of the work-posi-

tioning member for releasing the retaining means.

50. In a machine of the class described, a work-support, means for operating upon the work, the work-support and operating means being relatively movable toward and from one another, a work-positioning member, means for controlling the work-positioning member interposed between the support and operating means and being movable toward and from the support and laterally with respect to said support, means for temporarily retaining the controlling means against lateral movement, and means actuated in the movement of the work for releasing the retaining means.

51. In a machine of the class described, a work-support, means for operating upon the work, the work-support and operating means being relatively movable toward and from one another, a work-positioning member, means for controlling the work-positioning member interposed between the support and operating means and being movable toward and from the support and laterally with respect to said support, means for temporarily retaining the controlling means against lateral movement, and means arranged to be shifted by the movement of the work in co-operation with the controlling means for releasing the retaining means.

52. In a machine of the class described, a work-support, means for operating upon the work, the work-support and operating means being relatively movable toward and from one another, a work-positioning member, means for controlling the work-positioning member interposed between the support and operating means and being movable toward and from the support and laterally with respect to said support, means for temporarily retaining the controlling means against lateral movement, and means actuated in the movement of the controlling means toward and from the support for releasing the retaining means.

53. In a machine of the class described, a work-support, means for operating upon the work, the work-support and operating means being relatively movable, work-positioning means, means for controlling the work-positioning means movable to positions between and at one side of the work-support and operating means, said positioning and controlling means being differentially movable, and means under the influence of the differential movement for governing the position of the controlling means.

60. 54. In a machine of the class described, a work-support, means for operating upon the work, the work-support and operating means being relatively movable, work-positioning means, means for controlling the work-positioning means movable to posi-

tions between and at one side of the work-support and operating means, said positioning and controlling means being differentially movable, means for temporarily retaining the controlling means in one position, and means under the influence of the differential movement for releasing the retaining means.

55. In a machine of the class described, a work-support, a work-positioning member, means contacting with the work for controlling the work-positioning member, and means under the influence of the work for moving the controlling means relatively to said work.

56. In a machine of the class described, a work-support, means for operating upon the work, a work-positioning member, means for controlling the work-positioning member interposed between the support and operating means, and means under the influence of the work for moving the controlling means clear of the support and operating means.

57. In a heel-attaching machine, a jack-post, nailing mechanism, a band-clamp, and controlling mechanism for the band-clamp having a member movable between the jack-post and nailing mechanism.

58. In a heel-attaching machine, a jack-post, nailing mechanism, a band-clamp, and a gage for contact with a jacked shoe and co-operating with the band-clamp, said gage being movable transversely between the jack-post and nailing mechanism.

59. In a heel-attaching machine, a jack-post, nailing mechanism, a band-clamp, and controlling mechanism for the band-clamp having a contact-plate movable transversely between the jack-post and nailing mechanism.

60. In a heel-attaching machine, a jack-post, nailing mechanism, said jack-post and nailing mechanism being relatively movable into co-operation, a band-clamp, a gage movable toward and from the path of relative movement of the jack-post and nailing mechanism, and a band-clamp-stop connected with the gage.

61. In a heel-attaching machine, a jack-post to receive a lasted shoe, nailing mechanism, a band-clamp, a contact-plate movable between the jack-post and nailing mechanism and into contact with the shoe, and a band-clamp-stop connected with the contact-plate.

62. In a heel-attaching machine, a jack-post, nailing mechanism, a band-clamp, controlling mechanism for the band-clamp having a member movable between the jack-post and nailing mechanism, and a spring exerting its force to move the member toward such position.

63. In a heel-attaching machine, a jack-post, nailing mechanism, a band-clamp, con-

trolling mechanism for the band-clamp having a member movable between the jack-post and nailing mechanism, a spring exerting its force to move the member toward such 5 position, and a latch for holding the member against the tension of the spring clear of the jack-post and nailing mechanism.

64. In a heel-attaching machine, a jack-post, nailing mechanism, a band-clamp, controlling mechanism for the band-clamp having a member movable between the jack-post and nailing mechanism, a spring exerting its force to move the member toward such 10 position, a latch for holding the member 15 against the tension of the spring clear of the jack-post and nailing mechanism, and an actuator for the latch movable with the controlling mechanism.

65. In a heel-attaching machine, a jack-post, nailing mechanism, band-clamp mechanism, controlling mechanism for the band-clamp having a member movable between the jack-post and nailing mechanism, a spring exerting its force to move the member 20 toward such position, a latch for holding the member against the tension of the spring clear of the jack-post and nailing mechanism, and an actuator for the latch movable with the controlling mechanism 25 30 and having a portion for engaging the band-clamp mechanism.

66. In a heel-attaching machine, a jack-post, nailing mechanism, band-clamp mechanism, controlling mechanism for the band-clamp having a member movable between the jack-post and nailing mechanism, a spring exerting its force to move the member toward such position, a latch for holding the member against the tension of the 35 spring clear of the jack-post and nailing mechanism, and an actuator for the latch movable with the controlling mechanism 40 and having a portion movable under the influence of the work into engagement with 45 the band-clamp mechanism.

67. In a heel-attaching machine, a jack-post for supporting a lasted shoe, a nail-block, a slide having a way, a band-clamp mounted on said slide, a carrier movable in 50 the way and being provided with a stop for the slide, a gage mounted upon the carrier and being movable between the jack-post and nail-block or to one side thereof, a spring for moving the gage in one direction, 55 a latch for the gage movable upon the carrier, and a member connected to the latch and engaging the slide.

68. In a heel-attaching machine, a jack-post for supporting a lasted shoe, a nail-block, a slide having a way and a series of teeth, a band-clamp mounted on said slide, a carrier movable in the way and being 60 provided with a stop for the slide, a gage mounted upon the carrier and being movable 65 between the jack-post and nail-block or to

one side thereof, a spring for moving the gage in one direction, a latch for the gage movable upon the carrier, and a pawl pivoted on the latch for engagement with the slide-teeth.

70

69. In a heel-attaching machine, a jack-post to receive a lasted shoe, nailing mechanism, a band-clamp, a contact-plate movable between the jack-post and nailing mechanism and into contact with the shoe, a band-clamp-stop connected with the contact-plate, and an actuator for the contact-plate movable with the jack-post.

75

70. In a heel-attaching machine, a jack-post for supporting a lasted shoe, a nail-block, a slide, a band-clamp mounted on said slide, the slide having a way, a carrier movable in the way and being provided with a stop for the slide, a gage movable upon the carrier between the jack-post and nail-block or to one side thereof, and an actuator for the gage movable mounted upon the slide.

80

71. In a heel-attaching machine, a jack-post for supporting a lasted shoe, a nail-block, a slide having a way, a band-clamp mounted on said slide, a carrier movable in the way and being provided with a stop for the slide, a gage mounted upon the carrier and being movable between the jack-post and nail-block or to one side thereof, and an actuator for the gage movable by the band-clamp.

85

72. In a heel-attaching machine, a jack-post for supporting a lasted shoe, a nail-block, a slide having a way, a band-clamp mounted on said slide, a carrier movable in the way and being provided with a stop for the slide, a gage mounted upon the carrier and being movable between the jack-post and nail-block or to one side thereof, said gage having a cam-surface, and an actuator movable by the band-clamp and engaging the cam-surface.

90

73. In a heel-attaching machine, a jack-post, nailing mechanism, a band-clamp, controlling mechanism for the band-clamp having a member movable between the jack-post and nailing mechanism, a spring exerting its force to move the member toward such 110 position, a latch for holding the member against the tension of the spring clear of the jack-post and nailing mechanism, and an actuator for the member and latch movable with the band-clamp.

115

74. In a heel-attaching machine, a jack-post for supporting a lasted shoe, a nail-block, a slide having a way, a band-clamp mounted on said slide, a carrier movable in the way and being provided with a stop for the slide, a gage mounted upon the carrier and being movable between the jack-post and nail-block or to one side thereof, said gage having a cam-surface, a spring for moving the gage in one direction, a latch for 125 130

the gage movable upon the carrier, a member connected to the latch and engaging the slide, and an actuator mounted on the slide and having a portion contacting with the 5 cam surface and a portion co-operating with the latch member.

75. In a machine of the class described, a work-support, a work-positioning member, controlling means for the positioning member movable independently thereof to measure the work, and means for retaining the controlling means in its work-measuring position.

76. In a machine of the class described, a 15 work-support, a work-positioning member, controlling means for the positioning member movable to measure the work, and means under the influence of the work for retaining the controlling means in its work- 20 measuring position.

77. In a machine of the class described, a work-support, a work-positioning member, controlling means for the positioning member movable against the work at the opposite side from the work-support, and means for retaining the controlling means in this 25 position.

78. In a machine of the class described, a work-support, means for operating upon the 30 work, the work-support and operating means being relatively movable toward and from one another, a work-positioning member, means for controlling the work-positioning member interposed between the support and 35 operating means and being movable toward and from the support and laterally thereto, and means for locking the controlling means with respect to both movements.

79. In a machine of the class described, 40 a work-support, means for operating upon the work, the work-support and operating means being relatively movable toward and from one another, a work-positioning member, means for controlling the work-positioning member interposed between the support and operating means and being movable toward and from the support and laterally thereto, and means for locking the controlling means in proximity to the work with 45 respect to one movement and separated from the work with respect to the other movement.

80. In a machine of the class described, a work-support, means for operating upon the work, the work-support and operating 50 means being relatively movable toward and from one another, a work-positioning member, means for controlling the work-positioning member interposed between the support and operating means and being movable toward and from the support and laterally thereto, means for locking the controlling 55 means in proximity to the work with respect to one movement and separated from the work with respect to the other move-

ment, and means under the influence of the work for actuating said locking means.

81. In a machine of the class described, a support for a lasted shoe, a shoe-positioning member, a controlling member for the positioning member movable into contact with the heel-seat of the shoe, and means for locking the controlling member in the position determined by this contact.

82. In a machine of the class described, a work-support, a movable work-positioning member, a stop for the positioning member, means for setting the stop, and means for locking the stop in its set position.

83. In a machine of the class described, a work-support, a movable work-positioning member, a stop for the positioning member, means for setting the stop including a member contacting with the work, and means for retaining the stop in its set position independently of the work.

84. In a machine of the class described, a work-support, a movable work-positioning member, a stop for the positioning member, means for setting the stop including a member contacting with the work and being movable out of contact therewith, and means for retaining the stop in its set position when the contact member is separated from the work.

85. In a heel-attaching machine, a jack-post, nailing mechanism, a band-clamp, controlling mechanism for the band-clamp, and clutch mechanism for locking the controlling mechanism.

86. In a heel-attaching machine, a jack-post, nailing mechanism, a band-clamp, controlling mechanism for the band-clamp having a member interposed between the jack-post and nailing mechanism, a clutch joined to the controlling mechanism, and means actuated by the work for producing engagement of the clutch.

87. In a heel-attaching machine, a jack-post to receive a lasted shoe, nailing mechanism, a band-clamp, a contact-plate movable between the jack-post and nailing mechanism and into contact with the shoe, a band-clamp-stop connected with the contact-plate, and clutch mechanism associated with the stop.

88. In a heel-attaching machine, a jack-post to receive a lasted shoe, nailing mechanism, an band-clamp, a contact-plate movable between the jack-post and nailing mechanism and into contact with the shoe, a band-clamp-stop connected with the contact-plate, clutch mechanism associated with the stop, and means for actuating the clutch mechanism when the plate is in contact with the shoe.

89. In a heel-attaching machine, a support, a jack-post, a band-clamp, gage and stop mechanism for the band-clamp, and co-

operating clutch elements carried by the support and the gage and stop mechanism, and an actuator for the clutch connected to the band-clamp.

90. In a heel-attaching machine, a jack-post, a band-clamp, gage and stop mechanism for the band-clamp, and clutch mechanism for the gage and stop mechanism actuated in the movement of the jack-post.

91. In a heel-attaching machine, a jack-post, a band-clamp, gage and stop mechanism for the band-clamp, and clutch mechanism for the gage and stop mechanism controlled by the work.

92. In a heel-attaching machine, a jack-post, nailing mechanism, a band-clamp, controlling mechanism for the band-clamp, clutch mechanism for locking the controlling member, and an actuator for the clutch connected to the band-clamp.

93. In a heel-attaching machine, a support, a jack-post, a band-clamp, gage and stop mechanism for the band-clamp, co-operating clutch elements carried by the

25
5 support, a jack-post, a band-clamp, gage and stop mechanism for the band-clamp, co-operating clutch elements carried by the support and the gage and stop mechanism, and an actuator for the clutch connected to the band-clamp and including relatively movable elements.

94. In a heel-attaching machine, a support, a jack-post, a band-clamp, controlling 35 mechanism for the band-clamp, clutch mechanism for locking the controlling mechanism, and an actuator for the clutch including an element movable by the band-clamp and an element movable upon the 40 support.

In testimony whereof I have signed my name to this specification.

IRA C. BUCKMINSTER.
